UNITED STATES PATENT OFFICE.

JAMES A. RADCLIFFE, OF NEW YORK, N. Y., ASSIGNOR TO RADCLIFFE & COMPANY, OF NEW YORK, N. Y., A CORPORATION OF NEW YORK.

DESIGN FOR A BACK OF A PLAYING-CARD.

No. 38,829.

Specification for Design.

Patented Sept. 24, 1907.

Application filed August 16, 1907. Serial No. 388,929. Term of patent 14 years.

To all whom it may concern:

Be it known that I, JAMES A. RADCLIFFE, a citizen of the United States, residing at New York, in the county of New York and State of New York, have invented and produced a new, original, and ornamental Design for Backs of Playing-Cards, of which the following is a specification, reference being had to the accompanying drawing, forming a part thereof.

The figure is a plan view of the back of a playing card, showing my new design.

I claim:

The ornamental design for the back of a playing card, as shown.

JAMES A. RADCLIFFE.
